UNITED STATES PATENT OFFICE.

CARL ARVID CARLSON, OF EDMONTON, ALBERTA, CANADA.

GATE CONSTRUCTION.

Application filed September 9, 1927. Serial No. 218,485

This invention relates to a gate construction and more particularly to a construction wherein the principal object is to provide a gate having intermediate cross members which are of flexible material, so that the entire gate can be pulled back towards one side.

A further object is to provide a gate construction which will return to normal closed position upon being released by the operator.

With the foregoing and other objects in view, as will appear as the description proceeds, the invention consists of the novel construction, combination and arrangement of co-operating elements as hereinafter more specifically set forth, claimed and shown in the accompanying drawings forming a part of the present application, in which:

Fig. 1 is a side plan view of the preferred embodiment of my invention.

Fig. 2 is a top plan view of the operating means used in the preferred embodiment of my invention.

Fig. 3 is a plan view of one of the hangers.

Like numerals of reference designate corresponding parts throughout the different views.

At opposite sides of the gate, I provide uprights 4 and 5, having their lower ends imbedded along the side of the road bed. The upright 4 is slightly higher than the upright 5 and extending from the top of the upright 4 to the top of the upright 5, I provide a cover member C. This cover member C acts as a cover over the working parts, and over the track, as well as bracing the upper ends of the uprights 4 and 5 in their proper relationship to each other. On either sides of the upright 4, I provide uprights 6 and 7, having outwardly extending brackets 8 and 9 respectively. The lower ends of these uprights 6 and 7 are imbedded along the side of the road bed.

10 is an inclined track extending in parallel relationship to the cover C and having its opposite ends securely engaged, one near the upper end of the upright 4 and the other near the upper end of the upright 5. 11, 12 and 14 are hangers of U-shaped formation. 15 is a wheel mounted between the upper ends of the U-shaped member 12 and adapted to roll on the track 10. 16 indicates smaller rollers rotatably mounted intermediate the wheel 15 and the lower end of the U-shaped portion of the hanger 12. The purpose of these rollers will be hereinafter mentioned.

17 is an eye-bolt supported from the lower portion of the U-shaped hanger 12. 18, 19 and 20 are supporting cables having their upper ends attached to the eye-bolt 17 and the hangers 11, 12 and 14 respectively. The lower end of these supporting cables are attached to a suitable eye-bolt engaged in the ends of the suspended uprights 21, 22 and 23, which uprights are provided with intermediate flexible connections 24, 25 and 26.

The upright 5 is provided, on its inner face, with guide fingers 27 into which the upright 23 normally positions itself when the gate is closed and if desired a pin 28 may be transversely inserted through oppositely registering openings in the fingers 27 so as to retain the gate in closed position. 29 is an upright secured to the inner face of the upright 4 and to which the inner ends of the flexible connections 24 are attached.

30 and 31 indicate flexible cables, each having one end secured around one of the smaller rollers 16 in the hanger 14. These cables 30 and 31 extend upwardly over their respective smaller rollers 16 in the hangers 12 and 11. They then extend through their respective pulleys 32 and 33, extending outwardly then in approximately opposite directions towards the brackets 8 and 9. Each bracket is provided with a pulley 34 through which the cable will extend and hang downwardly therefrom. Each cable is provided with a suitable weight 35 near its free end.

36 is a buffer suitably supported inwardly from the upright 4 and provided with a spring 37, so that if the hangers 11, 12 and 14 are pulled up quickly, they will strike against this buffer 36 and when either of the cables 30 or 31 are released this spring 37, having been tensioned, will repel the hangers outwardly on the inclined track 10 so as to quickly return them to their normal position, thus closing the gate quickly.

The foregoing specification and annexed drawings disclose the preferred embodiment of my invention, but it is to be understood that minor changes may be resorted to in the commercial adaptation of my invention without departing from the scope of the invention as hereinafter claimed.

What I claim as new is:

A gate comprising uprights suitably braced at their upper ends; an inclined track supported between the upper ends of said uprights; hangers reciprocally mounted on

said track; cables extending through said hangers and one end secured to the outer one of said hangers; the said cables extending through pulleys supported on one of said uprights adjacent the upper end of said track; brackets supported on uprights spaced equidistant from said last mentioned upright; pulleys supported from each of said brackets; the ends of said respective cables extending

through these respective pulleys and suspending downwardly therefrom; suspension members supported from said hangers; gate uprights supported from the lower end of said suspension members and flexible connection means between said gate uprights. 10
16

In testimony whereof, I affix my signature.

CARL ARVID CARLSON.
